UNITED STATES PATENT OFFICE

99,702

DESIGN FOR AN AIRCRAFT LEVEL INDICATING DEVICE

Leslie F. Carter, Leonia, N. J., assignor to Sperry
Gyroscope Company, Inc., Brooklyn, N. Y., a
corporation of New York

Application October 18, 1935, Serial No. 59,109

Term of patent 7 years

To all whom it may concern:

Be it known that I, Leslie F. Carter, a citizen of the United States of America, residing at Leonia, in the county of Bergen and State of New Jersey, have invented a new, original, and ornamental Design for an Aircraft Level Indicating Device, of which the following is a specification, reference being had to the accompanying drawing, forming a part thereof.

Fig. 1 is a front elevation of the article as it appears on the aircraft instrument panel, the dotted lines representing that portion of the device normally behind the panel.

Fig. 2 is an enlarged face view of the station-

ary indicator representing an aircraft, as seen from the rear.

Fig. 3 is a side elevation of the complete article, a portion of the top being broken away to accommodate the lower portion of Fig. 2.

The drawing is shaded to show contrasting effect.

I claim:

The ornamental design for an aircraft level indicating device, as shown and described.

In testimony whereof I have affixed my signature.

LESLIE F. CARTER.
